P. O. BJORKE

MOTOR VEHICLE HEATER

Original Filed May 9, 1925

FIG. 4.

INVENTOR
Peter O. Bjerke
BY
Marshall + Stanley
ATTORNEYS

UNITED STATES PATENT OFFICE.

PETER O. BJORKE, OF CLIFFSIDE, NEW JERSEY, ASSIGNEE OF ONE-HALF TO WALTER J. MITCHELL, OF LYNNBROOK, LONG ISLAND, NEW YORK.

MOTOR-VEHICLE HEATER.

Application filed May 9, 1925, Serial No. 29,032. Renewed October 14, 1927.

This invention relates to heaters and particularly to heaters for vehicles, such as motor vehicles.

The invention has for its salient object 5 to provide a heater so constructed that a desirable temperature will be maintained and, furthermore, so constructed that the heater will retain its heat for a considerable period of time after the source of heat, such 10 as the engine exhaust has been discontinued.

Another object of the invention is to provide a heater that can be economically manufactured and installed.

Further objects of the invention will appear from the following specification taken 15 in connection with the drawings, which form a part of this application and in which

Fig. 1 is a top plan view partly in section and partly broken away illustrating a 20 heater constructed in accordance with the invention.

Fig. 2 is a sectional elevation taken substantially on line 2—2 of Fig. 1.

Fig. 3 is a transverse sectional elevation 25 showing the heater connected to a tank or container, and

Fig. 4 is an elevational view partly broken away illustrating the device mounted on a motor bus.

30 The invention briefly described consists of a heater comprising a by-pass conduit adapted for connection to the exhaust conduit of an internal combustion engine whereby the exhaust gases may be conducted through 35 the by-pass conduit. The by-pass conduit is jacketed and means is provided for circulating liquid through the jacket or jackets. In the embodiment of the invention shown, 40 a valve is provided for controlling the passage of the exhaust gas through the by-pass. Further details of the invention will appear from the following description.

Fig. 1 shows a portion 10 of a conduit leading from the exhaust manifold of an internal combustion engine. This conduit is connected at 11 to a pipe 12 having a valve 45 13 therein disposed between the inlet conduit 10 and an outlet conduit 14.

The pipe 12 is also connected to elongated 50 pipes 15 and 16 which in turn are connected together at their opposite ends by a pipe 17.

When the valve 13 is closed, the exhaust gas passes from the conduit 10 into pipe 12 and through pipes 15, 17 and 16 around the

valve 13 and outwardly through the outlet 55 pipe 14. When the valve 13 is open, the exhaust gas will pass through the valve and out through the pipe 14.

It will be understood that the pipes 15 and 16 will be located in the interior of the 60 vehicle or in such a manner as to communicate the heat therefrom to the interior of the vehicle.

In order to maintain the temperature inside the vehicle more uniform and to prevent excessive heat therein and, furthermore, in order to insure the retention of the heat for a considerable period after the engine has been shut down, the pipes 15 and 16 are enclosed in jackets 20 and 21. Each 70 of these jackets has a filling spout 22 covered by a cap 23 and each jacket also has a drain cock 24 at the bottom thereof.

In order to provide for the circulation of the fluid between the jackets and to maintain an equal amount of fluid in each jacket, the jackets are connected at the top thereof by pipes 25 and a connecting pipe 27. The jackets are also connected at the bottom portions thereof by a pipe 28. In this manner, the heated fluid will circulate through the two jackets and they will be maintained 80 at a substantially uniform temperature.

The fluid circulation system may also, if desired, be carried out in the manner of the 85 ordinary hot water heating system as shown in Fig. 3. In this figure, the jacket 20 is connected by a pipe 30 to a tank 31 which as shown in Fig. 4 may be mounted in the upper portion of the motor vehicle. The connection of the pipe 30 to the tank is made 90 between the top and bottom thereof and preferably below the normal level of the liquid therein. The tank is also connected by a pipe 32 to the bottom of the jacket 21. 95 A vent 34 is provided in the top of the tank 31.

In order to indicate to the vehicle operator the temperature of the fluid in the circulation system, a thermometer 35 may be 100 mounted in any suitable location as on the dash of the vehicle and be connected in a suitable manner to indicate the temperature of the water in the jackets.

From the foregoing description it will be 105 seen that simple, practical and economical means has been provided for heating a motor vehicle and that the device described will

operate to maintain a desirable temperature in the vehicle and, furthermore, the heat will be retained for a considerable time after the engine has been shut down.

5 Although one specific embodiment of the invention has been particularly shown and described, it will be understood that the invention is capable of modification and that changes in the construction and in the arrangement of the various cooperating parts 10 may be made without departing from the spirit or scope of the invention, as expressed in the following claims.

What I claim is:

15 1. In combination, an engine exhaust conduit, a plurality of longitudinally extending by-pass conduits connected to the exhaust conduit and adapted to receive exhaust gas therefrom and to conduct the hot gas longitudinally in a vehicle, a water jacket sur-

rounding each by-pass conduit and extending longitudinally in the vehicle and means for maintaining the circulation of water in the jackets and thereby maintaining the temperature uniform therein. 25

2. In combination, an engine exhaust conduit, a pair of longitudinally extending by-pass conduits connected to the exhaust conduit and adapted to receive exhaust gas therefrom and to conduct the hot gas longitudinally in a vehicle, a water jacket surrounding each by-pass conduit and extending longitudinally in the vehicle and conduits connecting said jackets at the top and at the bottom therof for maintaining the circulation of water in the jackets and thereby maintaining the temperature uniform therein. 30

In witness whereof, I have hereunto set my hand this 29th day of April, 1925.

PETER O. BJERKE.
